UNITED STATES PATENT OFFICE.

JOSEPH W. LEWIS, OF PHILADELPHIA, PENNSYLVANIA, ASSIGNOR TO THE ATLANTIC REFINING COMPANY, OF PHILADELPHIA, PENNSYLVANIA, A CORPORATION OF PENNSYLVANIA.

OIL-TREATING APPARATUS.

Application filed July 6, 1922. Serial No. 573,170.

My invention relates to apparatus for treating oil, and more particularly to apparatus for destructively distilling or cracking petroleum, petroleum distillate or petroleum residuum, under pressure, for the production of lower boiling point oils, as gasolene, etc.

In accordance with my invention, valve structure is provided for preventing passage or escape of oil or oil vapors from one portion of a pressure still system to another portion which has suffered breakage or rupture resulting in the escape of oil or vapors to the atmosphere or other region of lower pressure; and there are provided means for positively operating the valve structure, as by a power-operated motive device, preferably remotely controlled.

Further in accordance with my invention, valve structure is provided to close communication between a tubular or other structure in which the oil is subjected to high temperature and a reservoir or still, and there is provided a by-pass for allowing escape from the tubular or other structure to the reservoir or still of the oil or vapors retained or entrapped in the tubular or other structure.

My invention resides in apparatus of the character hereinafter described and claimed.

For an illustration of one of the various forms my invention may take, reference is to be had to the accompanying drawings, in which:

Fig. 1 is a vertical sectional view, some parts in elevation, of structure embodying my invention.

Fig. 2 is a fragmentary vertical sectional view of the heat absorbing structure.

Fig. 3 is a fragmentary plan of valve controlled lower circulating connection between the heat absorbing structure and the reservoir or still.

Fig. 4 is a fragmentary plan view of valve controlled upper circulating connection between the heat absorbing structure and the still or reservoir.

Fig. 5 is a side elevational view of a portion of the circulating connection and the by-pass.

In the drawings, there is shown, by way of example, a pressure still of the character

disclosed in my prior Letters Patent No. 1,844,448.

Referring to the drawings, S is a vertical cylindrical still or reservoir provided with the manholes 1, 1 near its bottom and top. The oil to be treated or cracked is pumped into the still S through the pipe 2, controlled by valve 3, and the residuum, tar or untreated oil is withdrawn through the pipe 4 controlled by valve 5.

Within the brickwork structure 6 are disposed the upper and lower horizontal drums D and D¹, connected, respectively, by pipes 7 and 8, with the interior of the still S at different levels or heights for ensuring circulation of the oil which is charged into and contained in the still S to a height considerably above the entrance of the pipe 7 into the still S.

The drums D, D¹ are interconnected by the numerous substantially vertical metal tubes or pipes T.

The chamber containing the drums D, D¹ and their connecting tubes T communicates through the opening 9 with the combustion chamber or fire box 10, in which is disposed the grate 11, to which fuel is delivered from the chute 12 through the hopper or stoker 13, the ashes falling into the pit 14 and delivered therefrom to ash-removing cars 15.

Baffles 16, Fig. 2, in the chamber containing the tubes T, serve to direct the hot gases from the combustion chamber 10 between and around the upper parts of the tubes T and the drum D and thence downwardly in contact with the lower portions of the tubes T and the drum D¹ and thence into the flue passages 17, 17, Fig. 2, which communicate with a stack or chimney, not shown.

The drums D, D¹ are provided with the manholes 18 and 19 to admit cleaners into the drums for removing carbonaceous and other deposits therefrom.

At the upper end of the still S is connected the vapor outlet pipe 20 delivering into the air-cooled condenser C which in turn delivers the vapors to a water-cooled condenser, not shown. The heavier oil vapors are condensed in the condenser C and returned to the still S through the runback connections 21.

In operation, the oil within the tubes T is subjected to a cracking temperature, the oil continuously circulating from the bottom of the still S through the pipe 8 to the drum D¹, thence upwardly through the tubes T to the drum D, thence through the pipes 7 to the still S, suitable pressure, as from 50 to 200 pounds per square inch or more, being exerted upon the oil in the still S, drums D, D¹ and tubes T, and throughout such part of the condensing system as may be suitable or desirable.

As indicated in Fig. 3, there is provided in the pipe connection 8 between the lower drum D¹ and the still S a valve structure 22 having the valve member 23 adapted to engage the valve seat 24 and thereby close communication between the drum D¹ and the still S. The valve member 23 is secured upon a valve rod 25, which is a continuation of the piston rod 26 attached to the piston 27 movable longitudinally within the cylinder 28, with opposite ends of which connect the pipes 29 and 30 for delivering to opposite sides of the piston 27 fluid under pressure, as liquid, or steam, or preferably air, for actuating the piston 27 to move the valve 23 to or from its seat 24.

The pipes 29 and 30 preferably communicate with or are continuations of the pipes 29 and 30 of Fig. 4, where those pipes communicate with the four-way valve 31 connected by pipe 32, controlled by valve 33, with the pipe 34, communicating with the source of fluid pressure, as, for example, with a reservoir of compressed air. With the valve 31 communicates also the exhaust pipe 35.

Between the pipe 7 and the still S, Fig. 4, there intervenes a valve structure 36, similar to valve structure 22, comprising the valve member 37 adapted to engage the valve seat 38 to close communication between the drum D and the still S. The valve member 37 is secured upon the valve rod 39 connected to the piston rod 40, upon which is secured the piston 41 movable longitudinally in the cylinder 42, to opposite ends of which connect the aforesaid pipes 29 and 30.

During normal operation of the pressure still the valve members 23 and 37 are raised from their seats 24 and 38, allowing the aforesaid circulation from the still or reservoir S to the heat absorbing structure D, T, D¹, back to the reservoir or still S, the oil vapors produced passing off through the vapor line 20 to the condensing structure C.

In case of rupture of a tube T or either of the drums D, D¹, with the resultant escape of oil under pressure into the atmosphere or hot gases, the escaping oil or vapors ignite and burn, and such combustion will continue by flow of oil under pressure from the still or reservoir S to the point of rupture.

To minimize the amount of oil and vapors so escaping and burning, the valves 23 and 37 are simultaneously operated by moving the control valve 31 to such position that air or other fluid under pressure is delivered from the pipe 34 through the valve 31 to and through the pipes 29, the fluid pressure then forcing the pistons 27 and 41 to the opposite ends of the cylinders 28 and 42, thereby moving the valves against their seats and closing communication between the heat absorbing structure and the still or reservoir S. To move the valves 23 and 41 to their normal or open positions, the valve 31 is moved in opposite direction to place the pipes 30 into communication with the pipe 34, with the result that fluid under pressure is introduced into the cylinders 28 and 42 at their opposite ends, thereby moving the pistons in opposite direction and moving the valves from their seats. When the pipe 29 is in communication with the supply pipe 34, the pipes 30 are brought into communication with the exhaust pipe 35 with the valve 31; and vice versa, when the valve 31 is in position to connect the pipes 30 with the pipe 34, the pipes 29 are brought into communication with the exhaust pipe 35; in both cases the fluid on the low pressure sides of the pistons 27 and 41 is allowed to escape or exhaust.

The valves 23 and 37, in the example illustrated and described, are not biased toward either their closed or open positions, but are positively operated to closed and open positions, the cylinders 28, 42 and their pistons 27 and 41 constituting motors or motive devices, which are power-operated for actuating or driving the valves.

While the paths of travel of the valves 23 and 37 are horizontal, it will be understood that their paths may be inclined or vertical, as may be suitable or desirable. By preference, though not necessarily, the valves 23 and 37 are operated independently of the influences of gravity and of the oil pressure.

The control valve 31 may be located at any suitable point, and is preferably situated remote from the still structure or that part thereof the effects of a rupture of or in which are controllable by the valves.

Should the valves 23 and 37 be inadvertently closed or inadvertently remain closed, continued heating of the heat absorption structure would cause damage thereto by excessive pressure developed therein, causing rupture of one or more of the tubes T or drums D, D¹, since circulation is prevented and the drums D, D¹ and their connecting tubes T then form a closed structure with no outlet for oil or vapors. To guard against such mischance, or any other effects due to closure of the valves 23 and 37, whether or not any of the heat ab-

sorption structure has been ruptured, I provide the by-pass line or pipe 43, preferably having the expansion bend 43^a, connecting at its one end with the pipe 7 and at its other end at 44 with a point or region beyond the valve 37 and in free communication with the still S, whereby upon continued application of heat to the heat absorption structure, oil or oil vapors may pass through the pipe 43 to the still S, thereby relieving the pressure upon the heat absorption structure and preventing damage thereto, and allowing escape of oil which, if retained within the heat absorption structure, would cause deposition of great amounts of carbon or carbonaceous material, with resultant elevation in temperature of the tubes T, and possibly also the drums D, D¹, causing them to burn out or become seriously deformed.

In order that oil or oil vapors may escape to the still S from the heat absorption structure, and yet prevent flow of oil from the still or reservoir S into the heat absorption structure through the pipe 43, there is preferably provided the check valve 45, of any suitable type. In the example illustrated, the check valve comprises a casing, within which is disposed a ball or similar member 46 adapted to engage the seat 47 and so prevent passage of oil from the pipe 43 into the pipe 7, the ball 46, however, lifting and allowing passage of oil or vapors from the heat absorption structure through the pipe 43 in the direction of the arrow, Fig. 5.

Preferably, the by-pass 43 is of relatively small cross section as compared with the circulating line 7, for ordinarily, with such smaller cross section, the pipe 43 is capable of allowing escape at suitable rate of oil or vapors from the heat absorption structure to the still S.

While the valves 23 and 37 are positioned adjacent the drum D¹ and still S, respectively, it will be understood that either of the valves may be located either adjacent the drum or the still S, or at any suitable point between them.

What I claim is:

1. The combination with pressure still structure comprising an oil containing chamber, heat absorption structure, circulating connections between them, and means maintaining super-atmospheric pressure within them, of valves for closing said circulating connections, a power-operated motive device for actuating each of said valves, a connection from a source of power to said motive devices, and a controller intervening between said source of power and said motive devices for causing simultaneous actuation of said valves to their closed positions.
2. The combination with pressure still structure comprising a vertical still, heat

absorption structure comprising a plurality of tubes, connections from the lower and upper ends of said tubes to said still at different levels thereof, and means maintaining super-atmospheric pressure in said still and tubes, of valves in said connections, and means for actuating said valves to open or closed positions simultaneously.

3. The combination with pressure still structure comprising a vertical still, heat absorption structure comprising a plurality of tubes, connections from the lower and upper ends of said tubes to said still at different levels thereof, and means maintaining super-atmospheric pressure in said still and tubes, of unbiased valves in said connections, and motive devices for said valves for moving them to open or closed positions simultaneously.

4. The combination with separated portions of oil treating apparatus operating under super-atmospheric pressure, of a connection between them passing liquid oil in one direction, a valve in said connection, means for closing said valve, a by-pass around said valve, and a check valve preventing flow of liquid through said by-pass in a direction the reverse of said one direction.

5. The combination with pressure still structure comprising an oil containing chamber, heat absorption structure, and a connection between them, of a valve in said connection for preventing flow of oil from said chamber to said heat absorption structure, and a by-pass around said valve for permitting flow from said heat absorption structure to said chamber when said valve is closed.

6. The combination with pressure still structure comprising an oil containing chamber, heat absorption structure, and a connection between them, of a valve in said connection for preventing flow of oil from said chamber to said heat absorption structure, a by-pass around said valve, and a check valve in said by-pass permitting flow from said heat absorption structure to said chamber and preventing flow in reverse direction.

7. The combination with pressure still structure comprising an oil containing chamber, heat-absorption structure, a connection between them, and means for maintaining super-atmospheric pressure in said chamber and heat-absorption structure, of a valve in said connection, a by-pass around said valve, and a check valve in said by-pass.

8. The combination with pressure still structure comprising an oil-containing chamber, heat-absorption structure, a circulating connection between them, and means for maintaining super-atmospheric pressure in said chamber and heat-absorption structure, of a valve in said connection, a connection having smaller cross section

than said circulating connection forming a by-pass around said valve, and a check valve in said by-pass preventing flow from said chamber to said chamber to said heat-absorption structure.

9. The combination with pressure still structure comprising an oil-containing chamber, heat-absorption structure, circulating connections between said chamber and said heat-absorption structure, and means for maintaining super-atmospheric pressure upon said chamber and heat-absorption structure, of valves in said connections, a power-operated motive device for each of said valves, means controlling said motive devices simultaneously for effecting movement of said valves to open or closed position simultaneously and a by-pass around one of said valves.
10. The combination with pressure still structure comprising an oil-containing chamber, heat-absorption structure, circulating connections between said chamber and said heat-absorption structure, and means for maintaining super-atmospheric pressure upon said chamber and heat-absorption structure, of valves in said connections, a power-operated motive device for each of said valves, means controlling said motive devices simultaneously for effecting movement of said valves to open or closed position simultaneously, a by-pass around one of said

valves, and a check valve in said by-pass preventing flow from said chamber to said heat-absorption structure.

11. The combination with pressure still structure comprising an oil-containing chamber, heat-absorption structure, circulating connections between said heat-absorption structure and said chamber at different levels thereof, and means for maintaining super-atmospheric pressure on said chamber and heat-absorption structure, of valves in said connections, and a by-pass around the valve in the connection with the higher level in said chamber.

12. The combination with pressure still structure comprising an oil-containing chamber, heat-absorption structure, circulating connections between said heat-absorption structure and said chamber at different levels thereof, and means for maintaining super-atmospheric pressure on said chamber and heat-absorption structure, of valves in said connections, a by-pass around the valve in the connection with the higher level in said chamber, and a check valve in said by-pass.

In testimony whereof I have hereunto affixed my signature this 30th day of June, 1922.

JOSEPH W. LEWIS.

- than said circulating connection forming a valves, and a check valve in said by-pass by-pass around said valve, and a check valve in said by-pass preventing flow from said chamber to said heat-absorption structure.
- 5 9. The combination with pressure still structure comprising an oil-containing chamber, heat-absorption structure, circulating connections between said chamber and said heat-absorption structure, and means 10 for maintaining super-atmospheric pressure upon said chamber and heat-absorption structure, of valves in said connections, a power-operated motive device for each of said valves, means controlling said motive 15 devices simultaneously for effecting movement of said valves to open or closed position simultaneously and a by-pass around one of said valves.
10. The combination with pressure still 20 structure comprising an oil-containing chamber, heat-absorption structure, circulating connections between said chamber and said heat-absorption structure, and means for maintaining super-atmospheric pressure up- 25 on said chamber and heat-absorption structure, of valves in said connections, a power-operated motive device for each of said valves, means controlling said motive devices simultaneously for effecting movement of 30 said valves to open or closed position simultaneously, a by-pass around one of said
11. The combination with pressure still 35 structure comprising an oil-containing chamber, heat-absorption structure, circulating connections between said heat-absorption structure and said chamber at different levels thereof, and means for maintaining 40 super-atmospheric pressure on said chamber and heat-absorption structure, of valves in said connections, and a by-pass around the valve in the connection with the higher level in said chamber. 45
12. The combination with pressure still structure comprising an oil-containing chamber, heat-absorption structure, circulating connections between said heat-absorption structure and said chamber at different 50 levels thereof, and means for maintaining super-atmospheric pressure on said chamber and heat-absorption structure, of valves in said connections, a by-pass around the valve in the connection with the higher level in 55 said chamber, and a check valve in said by-pass.

In testimony whereof I have hereunto affixed my signature this 30th day of June, 1922.

JOSEPH W. LEWIS.

Certificate of Correction.

It is hereby certified that in Letters Patent No. 1,593,905, granted July 27, 1926, upon the application of Joseph W. Lewis, of Philadelphia, Pennsylvania, for an improvement in "Oil-Treating Apparatus," errors appear in the printed specification requiring correction as follows: Page 1, line 40, after the word "plan" insert the word *view*, and line 54, for the number "1,344,443" read *1,364,443*; and that the said Letters Patent should be read with these corrections therein that the same may conform to the record of the case in the Patent Office.

Signed and sealed this 28th day of September, A. D. 1926.
